UNITED STATES PATENT OFFICE.

ELBERT EDGAR RICKS, OF PHILADELPHIA, PENNSYLVANIA.

WINDOW CLEANER AND WIPER.

1,341,590.

Specification of Letters Patent. Patented May 25, 1920.

Application filed November 18, 1919. Serial No. 338,880.

To all whom it may concern:

Be it known that I, ELBERT EDGAR RICKS, a citizen of the United States, residing at Philadelphia, in the county of Philadelphia and State of Pennsylvania, have invented new and useful Improvements in Window Cleaners and Wipers, of which the following is a specification.

My invention relates to a new and useful improvement in rotary window cleaners and wipers, and has for its object to provide an exceedingly simple and effective device of this description, which may be applied to car or other windows enabling a person from the inside to remove moisture, snow, sleet or other substances which may tend to obscure the vision through the window and also to wipe the window.

A still further object of my invention is to so construct the device that power may be applied thereto either by an independent motor or from the axles of the car whereby the cleaner may be operated continuously or intermittently under the control of the motorman or other attendant.

A still further object of my invention is to provide for the adjustment of one of the belt rollers so as to tighten the belts when needed.

With these ends in view, this invention consists in the details of construction and combination of elements hereinafter set forth and then specifically designated by the claim.

In order that those skilled in the art to which this invention appertains may understand how to make and use the same, I will describe its construction in detail, referring by numerals to the accompanying drawing forming a part of this application, in which:

Figure 1 is a front view of the window showing my improved rotary cleaner and wiper applied thereto.

Fig. 2 is a section at the line 2—2 of Fig. 1.

In carrying out my invention as here embodied, 1 represents a window frame carrying the glass 2, and to the outside of this frame is secured the journal brackets 3 and 4.

In the upper pair of brackets 3 is journaled the spindles 5 carrying the belt roller 6, this roller having the flanges 7 upon the ends thereof.

In the lower brackets 4 is journaled the

spindle 8 which carries the belt roller 9, and the bases of these brackets are slotted as indicated at 10 in order that this lower roller may be adjusted vertically.

The roller 9 also carries flanges indicated at 11, and 12 represents two hand belts which run upon two rollers 6 and 9 and are guided in their movements upon these rollers by the flanges 7 and 11 as will be readily understood. These belts may be made of any suitable material or may be in the form of linked chains or wire cables so long as they are sufficiently flexible to travel around the rollers.

13 represent the two cleaners and wipers the ends of each of which are secured to the belts in such manner that when the belts are put in motion first one of these cleaners will be drawn across the face of the glass while the other is moving in the opposite direction out of contact with said glass, but in turn when passing over one of the rollers will come in contact with the glass and be drawn over the surface thereof. This will permit the cleaning of the glass and then the wiping of the same, and these cleaners and wipers may be of any construction or of any suitable material preferably having a rubber strip for contact with the glass.

The spindles 5 and 8 have secured thereon the grooved pulleys 14 over which runs the hand belt 15, and this belt passes through suitable holes in the window frame and also runs over the pulleys 16 secured to the inner face of the window frame so as to bring this hand belt in easy reach of the motorman or other attendant. Thus it will be seen that the motorman may readily grasp this belt and pull the same upward or down and in so doing cause the belt rollers to revolve thereby causing the belts to travel with the cleaners and wipers which latter will verily clean and wipe the window as above described avoiding the necessity of the motorman opening the window and cleaning the outside thereof or going upon the outside for this purpose thus protecting him from exposure to the elements.

The belt rollers may be either made of wood or metal or pulleys used in the place of these rollers, said pulleys being secured upon the spindles 5 and 8 adapted to receive the belts and cause the travel thereof.

Of course I do not wish to be limited to the exact details of construction as herein shown as these may be varied within the

limits of the appended claim without departing from the spirit of my invention.

Having thus fully described my invention, what I claim as new and useful is:

- 5 A window cleaner and wiper for a window including a sash and the pane, comprising upper and lower spindles journaled on the outside of the sash, rollers on the spindles, continuous wiper belts passing over the
10 rollers and having wipers attached thereto,

pulleys on the spindles, pulleys mounted on the inner side of the sash and a continuous actuating belt passing over the said pulleys to have portions lie on the inside and outside of the sash whereby the device can be actuated. 15

In testimony whereof I have hereunto affixed my signature.

ELBERT EDGAR RICKS.
